[57] CLAIM

The ornamental design for an exercise platform, as
shown and described.

DESCRIPTION

FIG. 1 is a perspective view of an exercise platform,
showing my new design;

FIG. 2 is a top plan view thereof, shown fragmentarily
for ease of illustration;

FIG. 3 is a front elevational view of FIG. 2, the rear
view appearing the same;

FIG. 4 is a side elevational view of FIG. 2; and,

FIG. 5 is a bottom plan view of FIG. 2.

FIG. 1

FIG. 2

FIG. 3

FIG. 4
